(57) CLAIM

I claim the ornamental design for a exercise apparatus, as shown.

DESCRIPTION

FIG. 1 is a perspective view showing the front, top, and side of an exercise apparatus of the present invention;

FIG. 2 is an elevational view of a first side of the exercise apparatus of the present invention;

FIG. 3 is an elevational view of the rear of the exercise apparatus of the present invention;

FIG. 4 is an elevational view of a second side of a exercise apparatus of the present invention;

FIG. 5 is an elevational view of the front of the exercise apparatus of the present inventions;

FIG. 6 is a plan view of the top of the exercise apparatus of the present invention; and,

FIG. 7 is a plan view of the bottom of the exercise apparatus of the present invention.

The broken line structure is for illustrative purposes only and forms no part of the claimed design.
